Patented Mar. 2, 1915.

UNITED STATES PATENT OFFICE.

ROBERT S. BLAIR, OF NEW ROCHELLE, NEW YORK.

RECORDING APPARATUS.

1,130,469.

Specification of Letters Patent.

Patented Mar. 2, 1915.

Application filed August 14, 1907. Serial No. 388,477.

To all whom it may concern:

Be it known that I, ROBERT S. BLAIR, a citizen of the United States, residing at New Rochelle, in the county of Westchester and 5 State of New York, have invented certain new and useful Improvements in Recording Apparatus, of which the following is a full, clear, and exact description, such as will enable others skilled in the art to which it 10 appertains to make and use the same.

This invention relates to recording apparatus and more particularly to workmen's time recorders.

One of the objects thereof is to provide a 15 simple and practical time recorder susceptible of rapid use and adapted to form reliable records.

Another object is to provide simple means 20 for positioning the record receiving member of a time recorder with a high degree of accuracy and yet permit ready insertion and removal thereof.

Another object is to provide efficient and 25 reliable means for insuring against accidental or intentional misuse of a time recorder and falsification of its records.

Other objects will be in part obvious and in part pointed out hereinafter.

The invention accordingly consists in the 30 features of construction, combinations of elements, and arrangement of parts which will be exemplified in the mechanism hereinafter described and the scope of the application of which will be indicated in the 35 following claims.

In the accompanying drawing in which is shown one of various possible embodiments of this invention: Figure 1 is a sectional elevation thereof, certain parts being 40 diagrammatically shown in order to avoid obscuring the disclosure. Fig. 2 is a detailed view of a portion of locking mechanism. Fig. 3 is a similar view of the same part taken from the reverse side. Fig. 4 is 45 a similar view of another element of the locking mechanism. Fig. 5 is a sectional plan of the card receiving mechanism shown immediately above the same in Fig. 1.

Similar reference characters refer to 50 similar parts throughout the several figures of the drawing.

In order that certain features of this invention may be the more readily understood, it may here be noted that in the use of time 55 recorders in which a removable record card

is employed, it is often of prime importance that the card be placed precisely in the desired position, as otherwise an orderly and accurate record is difficult to obtain. It is also to be noted that the record card should 60 also fit in the receiver in such a manner as to permit its ready insertion and quick withdrawal without the chance of tearing the same. If it be attempted to attain these ends by gripping or justifying the card in a 65 manner similar to that long known in the printing art it is found that not only is the mechanism required for this purpose complicated and liable to derangement but its action is more or less inexact and does not 70 achieve the desired result. It may also be noted at this point that although means may be provided in time recorders of the nature of that herein shown for automatically limiting the depth of insertion of a record 75 card and thus preventing its being thrust downwardly to an undue extent for the purpose of falsifying the records, this does not prevent the lifting of the card and thus misplacing the record and forming it in a 80 space dedicated to the record of another day. The above and other defects are obviated and many positive advantages obtained in constructions of the nature of that 85 hereinafter described.

Referring now to the accompanying drawing, there is shown in Fig. 1 a casing 1 of a time recorder of the so-called card type provided with type wheels 3 disposed beneath an opening 2 formed in the casing. 90 These type wheels are adapted to print time or any function of time and may be driven from clock-work in any desired manner, the details of this mechanism not being shown as they form no part of the present invention. 95

Mounted beneath the opening 2 and adapted to receive a record card 4 and hold the same in operative relation to the type wheels is a card receiver 5. This receiver 100 comprises the horizontal straps 6 and 7, having formed at their ends the eyes 8 by which it is supported upon the vertical guide rods 9. The lateral card engaging members of the receiver 10 and 11 are 105 mounted as shown in a non-parallel and downwardly converging disposition, being connected in the present embodiment not only by strap 6 but by a cross member 12. As clearly shown in the drawings, the in- 110

clined portion of the card-receiver is preferably formed at an angle of less than 45 degrees with the direction of movement of the card in the receiver, and in this manner the card is firmly and accurately positioned even though it be merely resting in the receiver without being pressed downwardly therein. It is to be understood that the members 10, 11 and 12 are of channel conformation and adapted to embrace the card as best indicated in Fig. 5 of the drawings.

Secured to the straps 6 and 7 at one end of the same is a toothed member 13 against which a flat spring 14 presses the roller 15. It will thus be seen that the card receiver may be moved in a vertical direction along the guide rod 9 and that the same is held in a number of predetermined positions by the action of the roller 15 and its associated parts. It is also to be noted that if it be desired to move the receiver in a lateral direction, the same may readily be accomplished by providing the appropriate guide rods and it is to be noted that many features of this invention are adapted for use in a time recorder having a lateral movement of the card receiver.

Considering now the means whereby the receiver is raised, there is secured to the straps 6 and 7 a rack 16 intermeshing with a pinion 17 mounted upon a shaft 18 which may be journaled in bearings of any desired form. This shaft passes through the casing 1 and has loosely mounted upon its end a crank 19 in the hollow hub 20 of which is coiled a spring 21. Also mounted upon shaft 18 is a cylindrical indicator 22 adapted by means of the matter formed thereon to indicate through an opening or window 23 the day of the week for which the card receiver is set. Also mounted upon shaft 18 is a disk 24, the same being driven by clockwork in such manner as to complete a predetermined fraction of one revolution every twenty-four hours and being loosely mounted upon the shaft to turn freely thereon but held against lateral movement as by a suitable collar. This disk 24 as best shown in Fig. 4 of the drawings is provided with a concentric slot 25 having beveled ends and extending about one-seventh of the circumference of the disk. Mounted upon shaft 18 adjacent disk 24 is a locking member 26 provided with a beveled abutment 29 adapted in certain positions to register with and fit into the slot 25. Member 26 is keyed to the shaft 18 and slideable thereon and is urged toward the disk 24 as by the spiral spring 28. Mounted beneath the shaft 18 is an actuating lever 30 by which the forming of the record upon the record card is accomplished in any desired manner and shown for example in patent to Dey and Dey, No. 786,011, granted March 28, 1905, means for achieving this end being well known in this art.

Mounted adjacent lever 30 which is provided with a beveled lower edge is a swinging locking hook 31 having an abutment 32 adapted to engage the rear face of the member 26 which is so formed as to provide seven raised portions 27, the function of which will hereinafter be described in detail. A spring 33 is connected with the hook 31 and tends to swing the same away from the lever 30. 75

Recurring to the card receiver 5 there is mounted thereon at a point at which the lower edge of the record card rests a lever 34 pivoted at 35 and provided with the arm 36. Mounted adjacent this arm 36 is a 80 swinging rod 37 having pivotal centers 38 and 39 and provided with a spring 40 normally urging same in such a direction as to force the arm 36 toward the card receiver and consequently raise the short inner end 85 of the lever 34 upon which the card is to rest. The rod 37 is connected with a locking rod 41 mounted in guides of any desired type and resting at its free extremity against the locking hook 31 and holding the 90 same in lock position in the absence of a card in the card receiver.

The operation of the above described embodiment of this invention is substantially as follows: A record card may be inserted 95 through the opening 2 into the card receiver 5 and upon the actuating lever 30 being swung downwardly the same is forced against the type wheels and a record formed thereon in the well known manner. It is to 100 be noted that the card tapers downwardly to fit exactly the converging form of the receiver, and when it rests therein is held precisely in the desired position. The bottom of the card in this position rests in the 105 embodiment shown within the cross member 12 but it is to be noted that this member may be dispensed with and many of the advantages of this feature of my invention retained. Upon the impression being made 110 the card may be quickly snatched from the receiver without any tendency to bind therein, inasmuch as any upward movement loosens it in the receiver. The receiver is raised or lowered by a turning of the crank 19, the 115 spring 21 being placed under such tension as to overcome the effect of the spring 14 and snap the receiver upwardly or downwardly one step at a time. It is to be noted, however that the printing or actuating lever 120 30 cannot be thrown and the record made with the hook 31 in the locking position shown and the parts are so formed and disposed as to hold this hook in locking position through the abutment 32 whenever the 125 abutment 29 is out of registry with the slot 35 or whenever the abutment 32 is upon one of the raised portions 27. The disk 27 is so disposed moreover as to bring one of the raised portions 27 opposite the abutment 32 130

and throw the hook 31 into locking position whenever the card receiver is in one of its positions of rest and it will thus be seen that the only time during which the instrument can be used with the card in one of its predetermined stationary positions is when the abutment 29 fits within the slot 25 thus permitting the spring 28 to throw the locking member to the right and release the hook 31. During the movement of the receiver, however, as the same is snapped from one position to another and the abutment 32 passes into the depressions between the raised portions 27, the hook 31 is released and the use of the instrument is not prevented by the locking mechanism. It is to be understood that unless member 26 is set in proper position with respect to the clock-controlled disk 24, a raised portion 27 will force the hook under the printing lever and prevent use of the instrument. Hence the first workman in the morning must turn the crank until the abutment 29 enters the slot 25 thus permitting the member 26 to release the printing lever, and this turning of crank 19 will set the card-receiving members in such position that the record upon the card will be found in the proper space for the day upon which the record is made. Each day the disk 24 is driven through substantially the angle subtended by the slot 25 and each day the crank 19 must be turned through a corresponding angle and the record cards are correspondingly raised. There is provided, however, in the illustrative embodiment of this invention herein shown an auxiliary locking mechanism acting through the rod 41. This rod as above described is normally forced against the hook 31 by means of the spring 40 and holds it in locking position but is released upon a record card being inserted to its full depth whereupon its lower edge engages the inner end of the lever 34 and swings the arm 36 upwardly, thus swinging the rod 37 to the right and releasing the hook 31. It will thus be seen that it is prerequisite to the operation of this instrument that the card be inserted to its proper depth.

In order to avoid the chance of misinterpretation of certain terms used in this description and the following claims, it may here be noted that by the expression "printing mechanism" is meant record forming mechanism of any character and that the expressions "sides" and "bottom," or their equivalents, are used in a purely relative sense and are intended to cover equivalent members irrespective of the disposition of the card receiver as a whole.

It will thus be seen that there is provided an instrument in which the several objects of this invention are achieved, and the above described advantages are among others present. The entire construction is simple and

inexpensive and is of an essentially practical nature.

As various possible embodiments of the several features of this invention might be made and as this embodiment might be changed in many particulars without departing from the scope of the invention, it is to be understood that all matter contained in the above description or shown in the accompanying drawing is intended to be interpreted as illustrative and not in a limiting sense.

Having described my invention, what I claim as new and desire to protect by Letters Patent of the United States, is:

1. In a time recorder, in combination, printing means, means adapted to control the position of a record card with respect to said printing means, a hand actuated device for causing the operation of said printing means, a lock coacting with said hand actuated device to prevent the operation thereof, a clock driven member, and means adapted upon being brought into a predetermined relation to said clock driven member to properly position said second means and release said lock.

2. In a time recorder, in combination, printing means, a vertically movable device adapted to control the position of a card with respect to said printing means, a hand actuated lever, means connected with said lever adapted to form an impression from said printing means, a lock coacting with said lever, a clock driven member, means adapted upon being brought into a predetermined relation to said clock driven member to correctly position a record card with respect to said printing means and release said lock, and an indicating device adapted to register the day for which said card holding device is set.

3. In a time recorder, in combination, printing means, a movable card receiver having non-parallel non-yielding card engaging sides, and means adapted to move said receiver to vary the position of a card therein with respect to said printing means.

4. In a time recorder, in combination, printing means, a movable card receiver having non-parallel card engaging sides rigidly held in position, means adapted to move said receiver to vary the position of a card therein with respect to said printing means, and means adapted to guide said receiver in its movement with respect to said printing means, the non-parallel card-engaging sides being formed at an angle of less than 45 degrees with the length of a card in said receiver.

5. In a time recorder, in combination, printing means, a device having non-parallel sides adapted to engage opposite edges of a record card and hold the same in position and means to vary the position of said

- card with respect to said printing means with said card in engagement with said non-parallel sides and in operative relation to said printing means.
- 5 6. In a time recorder, in combination, printing means, a record card having an inclined edge, and a card receiver provided with a non-yielding inclined member adapted to engage said inclined edge and fit the 10 same while holding said card in operative relation to said printing means.
7. In a time recorder, in combination, printing means, a card receiver having both sides inclined and adapted to receive a 15 record card provided with inclined sides and hold the same in operative relation to said printing means.
8. In a time recorder, in combination, printing means, and a card receiver having an inclined side adapted to receive a record 20 card provided with an inclined side and having a member adapted to engage the bottom of a card in engagement with and substantially fitting said inclined side and 25 hold the same in a position adjacent said printing means.
9. In a time recorder, in combination, a record card receiver, the lateral card engaging members of which are rigidly held 30 spaced one from another at a greater distance at the top or entering end of the receiver than at the opposite end thereof whereby the card is readily fitted and accurately positioned there between.
- 35 10. In a time recorder, a record card receiver, the lateral card engaging members of which are held against rotary movement and converge in a direction away from the entering end of the receiver and the opposite 40 site end of which is provided with a member adapted to engage the bottom of a card substantially fitting said lateral members.
11. In a time recorder, a card receiver, one card-engaging side of which is shaped 45 to wedge a card firmly against the opposite side and limit its downward movement in the receiver.
- 50 12. In a time recorder, in combination, a card receiver, one card-engaging side of which is shaped to wedge a card firmly against the opposite side and limit its downward movement in the receiver, printing means, and means adapted to move said

inclined member to vary the position of said card with respect to said printing means. 55

13. In a time recorder, in combination, printing means, a card receiver having an inclined side and adapted to hold a card engaging said side in a position adjacent said printing means, and a record card having an inclined side and adapted to fit said receiver, said inclined portions being formed at an angle of less than 45 degrees with the length of the card-receiver while in operative relation to said printing means. 65

14. In a time recorder, in combination, printing means, means adapted to determine the position of a record card with respect to said printing means and limit the downward movement of said card to various pre-determined points, clock actuated means adapted periodically to move said limiting means throughout a predetermined space, means adapted to actuate said printing means, and means operative with said limiting means at any of said points adapted normally to prevent the actuation of said printing means and to permit actuation of the same upon a record card being placed in a predetermined relation to said second 80 mentioned means.

15. In a time recorder, in combination, a printing wheel, a card supporting device having a card engaging member inclined with respect to the plane of said printing 85 wheel, and means adapted to vary the position of said card with respect to said printing wheel and maintain it in engagement with said inclined member.

16. In a time recorder, in combination, a 90 card receiver, means adapted to form a record upon a card within said receiver, means adapted to adjust the position of said receiver with respect to said record, forming means, means adapted to lock said record 95 forming means, and means operative in all positions of said receiver adapted to release said lock upon a card being inserted therein to a predetermined depth.

In testimony whereof I affix my signature, 100 in the presence of two witnesses.

ROBERT S. BLAIR.
